BRASSIÈRE

Charles M. Sachs, West Newton, Mass., assignor to Formaid Co., Boston, Mass., a corporation of Massachusetts

Application April 13, 1951, Serial No. 14,812

Term of patent 7 years

(Cl. D20—4)

To all whom it may concern:

Be it known that I, Charles M. Sachs, a citizen of the United States of America, residing at West Newton, in the county of Middlesex and Commonwealth of Massachusetts, have invented a new, original, and ornamental Design for Brassière, of which the following is a specification, reference being had to the accompanying drawing, forming part thereof.

Fig. 1 is a front perspective of a brassière showing my new design;

Fig. 2 is a side elevation thereof; and

Fig. 3 is a rear view of the brassière.

I claim:

The ornamental design for a brassière, as shown.

CHARLES M. SACHS.
